United States Patent Office

Des. 192,734
Patented May 8, 1962

192,734

BUILDING BLOCK

Cameron D. Terry, P.O. Box 503, Lompoc, Calif.

Filed Apr. 17, 1961, Ser. No. 64,795

Term of patent 14 years

(Cl. D18—2)

FIG. 1.

FIG. 2.

FIG. 3.

FIG. 4.

FIG. 5.

I claim:

The ornamental design for a building block, substantially as shown and described.
